FLUSHING FLUID FOR HYDRAULIC
BRAKE SYSTEMS

Chester M. White, Rochester, N. Y., assignor
to Genesee Research Corporation, Rochester
N. Y., a corporation of New York

No Drawing. Application September 7, 1945,
Serial No. 615,078

5 Claims. (Cl. 252—153)

1

This invention relates to the production of a new and improved flushing fluid for use in hydraulic power transmission systems and is more particularly concerned with a non-corrosive composition useful in the flushing or "purging" of deteriorated brake fluids from hydraulic brake systems. More specifically, the invention contemplates and provides a novel flushing fluid of the foregoing character which not only possesses markedly improved solvent action on brake fluid deterioration products tending to accumulate on the metal and rubber surfaces of the hydraulic brake system but which also will not corrode the metal surfaces and cause the rubber parts to swell. Likewise encompassed within the scope of the invention is an improved process for flushing hydraulic brake systems employing the novel flushing fluid herein described and claimed.

Most hydraulic brake fluids in use at the present time comprise as their principal constituents castor oil and a solvent therefor. As is well known, castor oil has a tendency to oxidize and, in time, because of this tendency and also because of the tendency of the solvent to evaporate, hydraulic brake fluids made up of castor oil and solvent increase in viscosity to such an extent that the brake system becomes less sensitive and response to brake pedal action consequently becomes less positive. Because of this deterioration, it is advisable to flush the system periodically to remove the old fluid and clean the surfaces of the system where deterioration products have been deposited and accumulated.

So-called "commercial" alcohols, such as anti-freeze alcohol or completely denatured alcohol, have been widely used for this purpose. These alcohols, however, may and usually do contain agents which are detrimental to brake parts. For instance, gasoline and light mineral oils are in common use as denaturants in completely denatured alcohol and as evaporation retarders in anti-freeze alcohol. These materials are most undesirable in hydraulic brake system flushing because of their very vigorous deteriorating action on rubber piston cups which manifests itself in inordinate swelling.

The non-corrosive and improved solvent-action flushing fluid of the present invention comprises, as its essential ingredients, (1) an organic solvent, and (2) a solvent-action promoter. Desirably, the composition also contains an anti-corrosive agent and water.

As the organic solvent, lower straight chain aliphatic alcohols containing less than four carbon atoms in the chain have been found to be

2

the most effective, and as explained hereinafter, it is desirable that these alcohols be substantially anhydrous. Methyl alcohol is the most desirable because of its low viscosity and specific gravity and because of its efficiency in penetration of gummed or oxidized castor oil. Low specific gravity and viscosity make for added turbulence of flow, under pressure bleeding of the hydraulic system, which results in enhanced washing action. Efficiency in penetration aids in loosening or softening the gum deposits. Ethyl alcohol as well as propyl alcohol may be substituted for the methyl alcohol but, in the case of ethyl alcohol, denaturants such as petroleum derivatives must not be used because of the deteriorating tendencies hereinbefore referred to. Butyl alcohol is not preferred because of its known property of attacking rubber.

The aliphatic alcohol solvent is the major constituent of the improved flushing fluid and should be present to the extent of at least about 70% of the composition. The other components of the fluid are present in only comparatively minor percentages as will appear more particularly hereinafter.

A very important feature of the invention is the discovery that the solvent action of lower aliphatic alcohol solvents on deterioration products of hydraulic brake fluids may be enhanced and markedly increased by incorporating with the alcohol a comparatively small amount of a material herein described as a solvent-action promoter. The theory of action of this promoter is at present unknown, but it has been definitely established that the effect is not an additive one in the sense that the final improved solvent action is due merely to the additive solvent action of each material. Stated differently, the comparatively small amount of promoter employed causes an increment of increased solvent action of far greater magnitude than that which could be caused by any solvent action possessed by the promoter itself.

Preferred solvent-action promoters are cyclic alcohols which may be heterocyclic, carbocyclic or hydrocarbocyclic. Typical of these materials found operative for this purpose are furfuryl alcohol, cyclohexanol, alpha terpinol, benzyl alcohol, thymol, cresol (USP), 1,3,5 xylanol, phenol (40° M. P.), and catechol. Employed in the final flushing composition in proportions of from 1 to 20%, these promoters not only perform their disclosed function but are by actual test substantially non-corrosive to metals such as alumi-

num alloys, brass and iron, as well as substantially non-deleterious toward rubber.

Since the aliphatic alcohol solvent of the present flushing fluid composition has in and of itself a slight tendency to cause corrosion of iron and brass parts, it has been found advisable to include in the composition a comparatively small amount (1 to 5%) of an anti-corrosive agent. Cyclic amines, themselves non-corrosive to metals in the dilution indicated, are suitable for this purpose. Typical cyclic amines are: morpholine, methyl morpholine, ethyl morpholine, pipyridine, cyclohexylamine, dicyclohexylamine, benzothiazol, pyridine and aniline.

Aside from performing the function of cutting down corrosive action of the aliphatic alcohol solvent, these cyclic amines, surprisingly enough, likewise exhibit to a certain extent the power of promoting solvent action of the alcohol in the sense described hereinbefore. They therefore perform a dual function in the composition.

Completely anhydrous lower aliphatic alcohol solvents themselves react slowly with aluminum and, to overcome this corrosive effect, a small amount of water may be added to the composition. There is a limit, however, as to the amount of water which may be added since the presence of too much water will impair the rate of turbulence of flow and the efficiency of the composition in penetrating gummed or oxidized oils. The water content should be kept below approximately 5.0% for optimum results.

In general, and by way of recapitulation, the components of the improved flushing fluid are employed in the following approximate proportions:

	Per cent
Organic solvent	96.0 to 73.0
Solvent-action promoter	1.5 to 20.0
Anti-corrosive agent	1.5 to 5.0
Water	1.0 to 2.0

The following specific formulae have been found to be particularly efficient:

Example A

	Per cent
Anhydrous methyl alcohol	96.0
Furfuryl alcohol	1.5
Morpholine	1.5
Water	1.0

Example B

	87.5
Anhydrous methyl alcohol	87.5
1,3,5 xyleneol	10.0
Morpholine	1.5
Water	1.0

Example C

	91.2
Anhydrous ethyl alcohol	91.2
Morpholine	2.0
Cyclohexanol	2.0
Water	4.8

Example D

	96.0	65
Anhydrous methyl alcohol	96.0	65
Cyclohexanol	1.5	
Morpholine	1.5	
Water	1.0	

Example E

	96.0	70
Anhydrous methyl alcohol	96.0	70
Furfuryl alcohol	1.5	
Pipyridine	1.5	
Water	1.0	

It is to be understood, of course, that the fore-

going examples and formulae are but illustrative and by no means restrictive, the scope of the invention being defined in the appended claims.

What is claimed is:

5 1. A flushing fluid for hydraulic brake systems comprising the following ingredients in approximately the proportions indicated:

	Per cent
Anhydrous methyl alcohol	96.0
Furfuryl alcohol	1.5
Morpholine	1.5
Water	1.0

15 2. A flushing fluid for hydraulic brake systems comprising the following ingredients in approximately the proportions indicated:

	Per cent
Anhydrous methyl alcohol	87.5
1,3,5 xyleneol	10.0
Morpholine	1.5
Water	1.0

20 3. A flushing fluid for hydraulic brake systems comprising the following ingredients in approximately the proportions indicated:

	Per cent
Anhydrous ethyl alcohol	91.2
Morpholine	2.0
Cyclohexanol	2.0
Water	4.8

25 4. A substantially anhydrous flushing fluid for hydraulic brake systems comprising at least 70% of a lower straight chain aliphatic alcohol containing less than 4 carbon atoms, 1-20% of a compound effective to promote solvent action

30 a compound effective to promote solvent action of the alcohol on hydraulic fluid deterioration products and selected from the group consisting of furfuryl alcohol, cyclohexanol, alpha terpinol, benzyl alcohol, thymol, cresol, 1,3,5 xyleneol, phenol and catechol, and 1-5% of a compound effective to inhibit corrosion as well as promote solvent action of said alcohol and selected from the group consisting of morpholine, methyl morpholine, ethyl morpholine, pipyridine, cyclohexylamine, dicyclohexylamine, benzothiazol, pyridine and aniline.

35 5. A substantially anhydrous flushing fluid for hydraulic brake systems comprising at least 70% of a lower straight chain aliphatic alcohol containing less than 4 carbon atoms, 1-20% of a compound effective to promote solvent action of

40 the alcohol on hydraulic fluid deterioration products and selected from the group consisting of furfuryl alcohol, cyclohexanol, alpha terpinol, benzyl alcohol, thymol, cresol, 1,3,5 xyleneol, phenol and catechol, 1-5% of a compound effective to inhibit corrosion as well as promote solvent action of said alcohol and selected from the group consisting of morpholine, methyl morpholine, ethyl morpholine, pipyridine, cyclohexylamine, dicyclohexylamine, benzothiazol, pyridine and aniline, and not over 2% water.
